Primary Examiner — Barbara Fox*Assistant Examiner* — Harold E Blackwell, II(74) *Attorney, Agent, or Firm* — The Webb Law Firm(57) **CLAIM**

The ornamental design for a piping support tool, as shown and described.

DESCRIPTION

FIG. 1 is a front view of a piping support tool showing my new design;

FIG. 2 is rear view thereof;

FIG. 3 is left side view thereof;

FIG. 4 is a right side view thereof;

FIG. 5 is a top view thereof;

FIG. 6 is a bottom view thereof;

FIG. 7 is a left perspective view thereof;

FIG. 8 is a right perspective view thereof;

FIG. 9 is an exploded right perspective view thereof; and, FIG. 10 is a left perspective view showing the piping support tool in use.

Broken lines shown in FIGS. 1-10 form no part of the claimed design.

1 Claim, 10 Drawing Sheets(56)
